UNITED STATES PATENT OFFICE.

ARTHUR D. WHIDDEN, OF ELYRIA, OHIO.

ROTARY VALVE.

1,178,769.

Specification of Letters Patent. Patented Apr. 11, 1916.

Application filed April 8, 1915. Serial No. 20,036.

To all whom it may concern:

Be it known that I, ARTHUR D. WHIDDEN, a citizen of the United States, residing at Elyria, in the county of Lorain and State 5 of Ohio, have invented certain new and useful Improvements in Rotary Valves, of which the following is a specification.

My present invention relates to new and useful improvements in rotary valves for internal combustion engines, the primary object of my invention being the provision of an improved rotary valve of that general type disclosed in a patent granted to me February 9, 1915, and bearing the No. 15 1,127,837.

The primary object of my invention is the provision of a rotary valve which will control both the supply of explosive mixture and the exhaust in an engine of the four-cycle type and in which the capacity of the valve is doubled in order to insure complete charging of the engine cylinder upon the intake stroke of the engine and complete venting of the exhaust gases in the engine 20 cylinder upon the exhaust stroke of the engine.

Further objects of my invention consist in the provision of a rotary valve in which the ports are so arranged that pressure upon 30 the valve is balanced, in the provision of a water jacketing for cooling both the engine cylinder and the valve, and the provision means for lubricating the valve.

With these and other objects in view, my 35 invention will be more fully described, illustrated in the accompanying drawings, and then specifically pointed out in the claims which are attached to and form a part of this application.

40 In the drawings: Figure 1 is a central, vertical, longitudinal sectional view taken through a one cylinder internal combustion engine equipped with my improved rotary valve; Fig. 2 is a vertical sectional view 45 taken on the line 2—2 of Fig. 1, looking in the direction of the arrow; Fig. 3 is a horizontal sectional view taken on the line 3—3 of Fig. 1, showing the valve construction; Fig. 4 is a perspective view of the valve 50 removed from the valve casing; Figs. 5, 6, 7 and 8, are vertical sectional views taken on the lines 5—5, 6—6, 7—7 and 8—8 of Fig. 3, illustrating the relative positions of the ports of the valve and valve casing, the 55 valve being shown in exhaust position.

Corresponding and like parts are referred

to in the following description and indicated in all the views of the drawings by the same reference characters.

For the sake of clearness and to insure a full understanding of the construction and operation of my improved valve I have illustrated it in connection with a one cylinder, four-cycle internal combustion engine of conventional type, it being understood that it may be employed with equally good results with an engine having any number of cylinders. The engine consists primarily of two castings 10 and 11, the former constituting the crank casing of the engine and the latter including the cylinder and valve casing, together with the various passages leading from the cylinder to the casing. These castings are bolted or otherwise secured together in the usual manner and the front and rear walls of the casting 10 or crank case are provided with alined bearings 12 to receive a crank shaft 13.

The cylinder and valve casing are preferably cast as a unit in order to prevent all leakage, either of the explosive mixture, exhaust gases or water from the water jacketing of the cylinders and valve and said casting includes an outer casing 14, an inner casing or cylinder proper 15, a hollow cylindrical valve casing 16, extending in spaced relation above the top of the cylinder and longitudinally of the outer casing 14, and ducts 17 and 18 forming passages for the admission and emission of the gases to and from the cylinder. The space within the outer shell 14, surrounding the cylinder, valve casing and ducts, forms a water chamber through which circulation of water may be maintained in any desired manner, not shown, to prevent over-heating of the cylinder and valve. A piston 19 is mounted in the cylinder and operatively connected by the piston rod 20 with the wrist pin 21 of the crank shaft. The valve casing 16 opens at its ends through the front and rear walls of the outer casing 14 and one end of the valve casing is closed by a cap 22, while the other end is closed by a cap 23 provided centrally with an opening 24 for the passage of a trunnion formed upon one end of the valve proper and by which the valve is rotated in its casing, as will be later explained.

The valve casing is provided along the horizontal plane of its axis and upon both sides with a multiplicity of ports 25, 26, 27 and 28, the ports upon one side being ar-

ranged in staggered relation with respect to the ports upon the other and ducts 29 lead from these ports to aligned ports in the casing 14. The duct 17 communicates with that duct 29 communicating with the port 26, while the duct 18 communicates with that duct 29 communicating with the port 27. An intake manifold 30 leads from a carburetor 31 to that duct 29 communicating with the port 25 and an outlet or exhaust manifold 32 leads from that duct 29 communicating with the port 28, the ports 25 and 28 thereby constituting inlet and exhaust ports of the valve casing.

15 A valve proper 33 is mounted for rotation in the valve casing and this valve consists of a hollow cylindrical shell or body fitting closely within the valve casing and bearing at its ends against the caps 22 and 23, one end of the valve being provided with a centrally formed trunnion 34 which projects through the opening 24 of the cap 23. This trunnion carries a sprocket 35 and a sprocket chain 36 is trained about the sprocket 35 and about a second sprocket 37 carried upon the forward end of the crank shaft 13, the relative size of the sprockets being such that the valve is turned during every two revolutions of the crank shaft. Although I have shown the valve as driven by a chain and sprockets from the crank shaft, it will of course be understood that the valve may be driven in any suitable manner, the idea being merely to provide means for rotating the valve at half the speed of rotation of the crank shaft. This valve body is divided into end chambers 38 and 39 by an intermediate, transverse partition wall 40, the fuel supply to the engine cylinder being supplied through both these chambers simultaneously and the exhaust gases from the engine cylinder also passing through these chambers, as will be later pointed out. For this reason, the peripheral wall of the chamber 39 is provided with ports 41 and 42 adapted to simultaneously register with the valve casing ports 25 and 26, respectively, in one position of the valve to permit explosive gases coming from the intake manifold 30 to pass into the chamber 39 and through the port 26 and ducts 29 and 17 into the cylinder 15. The wall 40 of the valve is also provided with a passage 43 and a duct 44 is formed within the chamber 38 to communicate between this port 43 and a port 45 formed in the wall of the valve and in longitudinal alignment with the port 41. This port 45 consequently registers with the port 27 and when the ports 41 and 42 register with the ports 25 and 26, it will be clear that a portion of the explosive gases entering the chamber 39 will pass through the duct 44 to the duct 18 and so to the engine cylinder, the charge therefore entering the engine cylinder through both of the

ducts 17 and 18. In like manner, the peripheral wall of the chamber 38 is provided with ports 46 and 47 adapted to simultaneously register with the ports 28 and 27 in one position of the valve to permit exhaust gases from the engine cylinder to pass through the duct 18 and chamber 38 to the exhaust manifold 32. Furthermore, the wall 40 is provided with a second port 48 and a duct 49 leads from this second port 75 to a port 50 formed in the peripheral wall of the chamber 39 to register with the port 26 of the valve casing when the ports 46 and 47 of the valve register with the ports 28 and 27 of the valve casing. Because of this, 80 exhaust gases from the cylinder will also pass through the duct 17 and duct 49 to the chamber 38 and from this chamber to the exhaust manifold 32. At this point it should be noted that, looking at the engine from the 85 front, the rotary valve turns in a clockwise direction. With this in view, it should be noted that the port 41 is formed at substantially 107 degrees angle to the port 50 which is formed in the same horizontal 90 plane with the ports 46 and 47 and that the port 47 is formed at substantially an angle of 107 degrees to the port 45 which is in the horizontal plane of the ports 41 and 42. In other words, the ports are so arranged 95 that, assuming the valve is in the position shown in the drawings, which is midway of its exhaust movement, 107 degrees turning movement in a clockwise direction will bring it to a position midway of its intake 100 with the port 41 of the valve registering with the port 25 of the casing, the port 42 registering with the port 26 of the casing and the port 45 registering with the port 47 of the casing.

105 The inner face of the valve casing, about each of its ports, is cut-away to seat a packing ring 51 of any suitable type in order to prevent leakage between the valve and valve casing and the outer ends of those ducts 29 which communicate with the ducts 17 and 18 are closed by threaded plugs 52 to prevent escape of gases from the engine.

110 The top of the outer casing 14 and the upper portion of the valve casing 16 are provided with aligned bores to receive a lubricating pipe 53 by means of which oil may be supplied to the valve between it and its casing. A threaded passage 54 leads through the casing 14 and upper portion of 115 the cylinder wall 15 to receive a spark plug by which the charges in the cylinder may be ignited.

120 From the foregoing description, taken in connection with the drawings, the manner 125 of operation of my rotary valve will be readily understood and but slight description is necessary.

125 Assuming that the engine is at the middle of its exhaust stroke and that the valve is 130

at a corresponding position, which is the condition of the engine and valve illustrated in the drawings, the exhaust gases from the cylinder 15 will pass through the duct 17, alined ports 26 and 50, the duct 49 and the port 48 to the chamber 38 and also through the duct 18 and alined ports 27 and 47 to the chamber 38. From this chamber, the exhaust gases will pass through the alined ports 46 and 28 to the exhaust manifold 32. It will, therefore, be clear that the exhaust gases escape from the cylinder through both the ducts 17 and 18, the gas from both these ducts passing through the chamber 38, but never entering the chamber 39. It will also be clear that upon a little over a quarter rotation of the valve in a clockwise direction, the ports 46 and 47 will both pass the valve casing ports 28 and 27, respectively, as also will the port 50 with respect to the port 26. This approximate quarter revolution of the valve will, however, bring the port 41 of the valve into registration with the port 25 of the casing and the port 42 into registration with the port 26 of the casing. Furthermore, the port 45 will, under these circumstances, register with the valve casing port 27. Suction of the engine will thereupon draw an explosive mixture from the carbureter through the intake manifold 30 and alined ports 51 and 41 into the valve chamber 39. The explosive mixture will pass from this valve chamber partially through the alined ports 42 and 26 and the duct 17 to the engine cylinder and partially through the duct 44 and alined ports 45 and 27 and duct 18 to the engine cylinder. It will, therefore, be clear that all fuel drawn into the cylinder will pass through the chamber 39 and none of it through the chamber 38 of the valve, and that fuel will be supplied to the cylinder through both the ducts 17 and 18. The above described position of the valve, of course, constitutes the mid-position of the intake stroke of the engine.

As will be seen by reference to Figs. 5 to 8 of the drawings, all ports of the valve will be out of registration with the corresponding ports of the valve casing during the succeeding half revolution of the valve which constitutes the compression and explosion strokes of the engine. Upon a further turning of the valve to complete the whole revolution, which takes place once during each two complete revolutions of the crank shaft, the valve will again occupy the position shown in the drawings, which is the exhaust position thereof.

Having thus described the invention, what is claimed as new is:

1. In a gas engine valve, a cylindrical valve casing having an inlet port, an outlet port and a pair of ports, both adapted for communication with an engine cylinder, a

hollow cylindrical valve closed at its ends rotatable in the valve casing and having means for successively establishing communication between the inlet port and both ports leading to the engine cylinder and the outlet port and both ports leading to the engine cylinder. 70

2. In a gas engine valve, a cylindrical valve casing having an inlet port, an outlet port and a pair of ports, both adapted for communication with an engine cylinder, a hollow cylindrical valve closed at its end rotatable in the valve casing, a partition extending transversely of the valve and dividing it into inlet and exhaust chambers, 80 ports in the walls of the chambers adapted, in certain positions of the valve, to register with the inlet and outlet ports of the valve casing, a pair of ports in each chamber adapted to register with the ports communicating with the engine cylinder, and ducts leading one from one port of each pair of ports into the other chamber. 85

3. In a gas engine valve, a cylindrical valve casing having an inlet port, an exhaust port 90 and a pair of ports adapted to communicate with an engine cylinder, a hollow cylindrical valve closed at its ends rotatably mounted in the valve casing, a partition wall extending transversely of the valve to provide 95 inlet and exhaust chambers, the inlet port and one of the cylinder ports of the valve casing being opposite one chamber and the exhaust port and the other cylinder port of the valve casing being opposite the other 100 chamber, an inlet port formed in the valve and adapted to register with the inlet port of the valve casing, an exhaust port formed in the valve adapted to register with the exhaust port of the valve casing, a pair of 105 ports formed in the wall of one chamber and adapted to register with one of the cylinder ports, one when the inlet port of such chamber registers with the inlet port of the casing and the other when the exhaust port of 110 the other chamber registers with the exhaust port of the valve casing, a duct leading from said latter port through the partition wall to communicate with the exhaust chamber, the wall of the exhaust chamber having a 115 pair of ports adapted to register with the other port leading from the cylinder, one of said latter ports being adapted to register with its valve casing port when the exhaust port of the valve registers with the exhaust 120 port of the valve casing and the other port being adapted to register with the cylinder port when the inlet port of the valve registers with the inlet port of the valve casing, and a duct establishing communication between such port and the inlet chamber of 125 the valve casing.

4. In a gas engine valve, a cylindrical valve casing having an inlet port, an exhaust port and a pair of ports, each adapted 130

to communicate with an engine cylinder, a hollow cylindrical valve closed at its ends rotatable in the valve casing, a partition extending transversely of the valve and dividing it into inlet and exhaust chambers, the valve being provided at either side of the partition with ports adapted to successively register with the cylinder ports of the valve casing, ducts leading from such ports in the valve through the partition wall of the valve, whereby in certain positions of the valve communication may be established from one of the ports communicating with the cylinder to that chamber not opposite such port, additional ports formed in the wall of the valve to successively register with the ports in the valve casing which communicate with the cylinder, an inlet port formed in the wall of one valve chamber adapted to register with the inlet port of the valve casing, and a port formed in the wall of the other chamber adapted to register with the exhaust port of the valve casing.

5. In a gas engine valve, a cylindrical valve casing having an inlet port and an exhaust port, a pair of ports each adapted to communicate with an engine cylinder, a hollow cylindrical valve closed at its ends rotatable in the valve casing, a partition divid-

ing the valve into inlet and exhaust chambers, the valve having a port formed in the wall of the inlet chamber to communicate with the inlet port of the casing and a port formed in the wall of the exhaust chamber to communicate with the exhaust port of the casing, and means operable upon rotation of the valve for successively placing both of the cylinder ports of the casing in simultaneous communication with the valve chambers.

6. In a gas engine valve, a cylindrical valve casing having a pair of ports adapted to communicate with an engine cylinder, an inlet port and an exhaust port, and a cylindrical valve mounted in the casing and formed with ports and passages adapted, in one position of the valve, to establish communication between the inlet port and both of the first named ports and in another position of the valve to establish communication between the exhaust port and both of the first named ports.

In testimony whereof I affix my signature in presence of two witnesses.
